UNITED STATES PATENT OFFICE.

GEORGE E. SEYMOUR, OF NEW ALBANY, INDIANA, ASSIGNOR TO AMERICAN CAR AND FOUNDRY COMPANY, OF ST. LOUIS, MISSOURI, A CORPORATION OF NEW JERSEY.

FOLDING LAVATORY.

1,078,314.

Specification of Letters Patent. Patented Nov. 11, 1913.

Application filed March 6, 1913. Serial No. 752,417.

To all whom it may concern:

Be it known that I, GEORGE E. SEYMOUR, residing at New Albany, Indiana, and being a citizen of the United States, have invented 5 certain new and useful Improvements in Folding Lavatories, of which the following is a full, clear, and exact description, such as will enable others skilled in the art to which it appertains to make and to use the 10 same, reference being had to the accompanying drawings, which illustrate the preferred form of the invention, though it is to be understood that the invention is not limited to the exact details of construction shown 15 and described, as it is obvious that various modifications thereof will occur to persons skilled in the art.

In said drawings: Figure 1 is a front view of a device embodying this invention showing 20 the operative parts in closed position and the relative form and arrangement of the concealed parts in dotted lines. Fig. 2 is a vertical central section of Fig. 1 showing the concealed parts in dotted lines and 25 the operative position of some of the parts in dot and dash lines. Fig. 3 is a half section on the line 3—3 of Fig. 2 looking in the direction of the arrow. Fig. 4 is a plan view of the preferred form of faucet employed in this device with the cap piece and 30 tension spring removed and shows the operative part of said faucet in closed position. Fig. 5 is a similar view showing the cold water inlet to the faucet opening. Fig. 6 is 35 a similar view showing the position of the parts when warm water is being used, and, Fig. 7 is also a similar view showing the position of the parts when steam is being used.

40 This invention relates to folding lavatories of the all-steel type and is particularly adapted to exposed plumbing as used in all-steel railroad car construction.

It comprehends in its adaptation a light, 45 neat and sanitary device of maximum capacity occupying a minimum of space, capable of being attached and detached with great facility.

It also comprehends a simple and novel 50 method and means for supplying water at all ranges of temperature from a single cold water inlet, the temperature and volume of such supply being entirely under control of the user.

55 Referring to the drawings, a suitable wall bracket is employed which comprises a

frame having a flat exposed surface 1, the edge 2 thereof being beveled. The interior of the frame is recessed forming vertical and horizontal faces 3, the inner portion of these 60 surfaces being beveled inward as at 4 forming a pocket for the basin when in folded position. The inner beveled portion 4 of the frame is cut away some distance from the bottom of the frame forming a stop at 65 5 for the basin or an extension thereof when the said basin is in horizontal position. Within the wall bracket frame and overlapping the inner edges of the same is located a flat metallic piece 6 to which a faucet 7 70 and the soap and brush tray 8 are secured, this metallic piece is also provided with rivet holes for the purpose of securing to the walls of the car the wall bracket frame. This metallic piece is also arranged to overlap the inner edge of the slop hopper 9 75 which is preferably formed as flat as possible so that it shall not extend beyond the greatest projection of the device when in closed position. The slop hopper is provided with a cylindrical outlet nipple 10 that is adapted to enter the drain pipe. The upper outer edge of the slop hopper is beveled inwardly to about the level of the wall bracket frame.

80 The basin rim 11 comprises a metallic pressing somewhat square in shape and outlined by an upwardly extending flange 12 having its projecting edge inturned to eliminate any rough projections thereon and the 85 said pressing is provided with an opening 13 having an inturned flange 14 outlining the same and the basin 15 is attached to the underside of the rim either by riveting or welding, or the entire basin may be formed 90 as one integral pressing. The basin rim 11 is extended backward beyond the hinge and inclined downwardly in the center at the rear of the basin opening, such rear extension being designed to approximately fill the 100 wall bracket recess and contact with the stop 5 at its edges to hold the said basin in horizontal position. The basin flange 13 is cut away as at 15 to form an outlet or drain for water in the basin.

105 The basin hinge comprises a cylindrical bar 17 which is preferably held in sockets 18 attached to the flat surface 1 of the wall bracket frame and in sockets 19 secured to the basin. The bar 17 is provided with spiral cushioning springs 20 preferably converging in their convolution toward the cen-

ter where each spring has an offset 21 bearing upon the basin rim 11. These springs also have offsets 22 bearing upon the face of the slop hopper and are designed to be of 5 a sufficient resistance to sustain the basin in any intermediate position and to relieve the jar consequent to a sudden shifting of the basin from closed to open position. On the inside end of the basin rim there is located 10 a rubber or other form of buffer 23 which is adapted to abut the inner face of the slop hopper 9 when the basin is in closed position.

The upper flat surface 1 of the wall 15 bracket frame is provided with a suitable button or catch 24 to maintain the basin closed and the basin is provided with a suitable finger hole or handle 25 adapted to facilitate raising or lowering of the same.

20 The faucet 7 employed in this device preferably comprises a single casting having a single outlet spout 7^a and is provided with a threaded inlet 26 for water and a threaded inlet 27 for steam, both of which 25 are connected with a common mixing chamber 28 formed in the body of the faucet casting. Within the mixing chamber 28 is a single valve 29 provided with a concentric slot 30 shown particularly in Figs. 4, 5, 6, and 7 30 which is adapted to coincide with the water inlet and permit the said chamber 28 to fill with water. The valve is also provided with concentric slot 31, also illustrated in Figs. 4, 5, 6 and 7, which is adapted to coincide with the steam inlet and permit steam to mix with the water in the chamber. The 35 valve is of the wiping rotary type and is held in its seat by means of spiral spring 32 which bears upon the cap piece 33 of the 40 said mixing chamber 28. The upper end of the spindle of valve 29 is squared and a handle 34 secured thereto by means of a clamp nut 35.

The cold water supply is carried through 45 a pipe 36 which is shown in the drawing as extending downward and lying with the upper right hand portion of the wall bracket frame and bent in such manner as to cross the face of the device within the recess of 50 the wall bracket frame to the water inlet side of the faucet 7. The steam pipe 37 is shown as extending upwardly and lying within the lower left hand portion of the wall bracket frame and bent in such manner as to cross the face of the device within 55 the recess of the same to the steam inlet side of the faucet 7. This arrangement is, however, only conventional and may be varied to suit the position of the supply inlets.

60 The operation of the device with particular reference to Fig. 2 and to Figs. 4, 5, 6 and 7 is as follows: The catch 24 having been released, the basin rim 11 is rotated by

a downward pull on the handle 25 against the resistance of the cushioning springs 20 65 until the rear projecting portion 15 of the said basin rim abuts the stop 5 on the interior bevel of the wall bracket frame. The handle or cock 34 of the faucet 7 may then be turned or pulled outward until the concentric slot 30 of the valve 29 coincides with the cold water inlet into the chamber 28 when cold water will flow into the basin. If warm or hot water is desired the handle 75 34 is moved farther forward until the concentric steam slot 31 of the valve 29 coincides with the steam inlet 27 into the chamber 28 and the evaporation of steam in the said chamber 28 will heat the water to any desired degree in proportion to the amount 80 of steam admitted.

It will be observed that Fig. 7 represents a relationship of the concentric slot so arranged that only steam will be supplied as only the steam slot 31 coincides with the 85 steam inlet 27 and the cold water port of the valve 29 is closed. This relationship has certain advantages such as using steam for melting ice from the lock of a mail bag or for other purposes of such nature. 90

To evacuate or dump the water in the basin 14, the basin is forced upward and the water flows through the cut away portion of the flange 13 down the rearwardly extending incline into the slop hopper 9 and 95 thence into the outlet pipe. When the basin pipe is in uppermost position catch 24 is slipped in place and the device thereby is closed.

This device is particularly adaptable to 100 mail car service equipment from the facility with which it can be assembled in place or taken down.

It will be observed that the outlying flange of the basin rim is provided with a notch 105 38 on its inner surface. This notch is adapted to bridge the water and steam inlet pipe and permit the basin rim to fit snugly within the recess of the wall bracket.

What I claim is:—

In a device of the class described, a recessed wall bracket frame having a rectangular recess, a basin having a substantially rectangular flange closable within said recess, a faucet within the recess of the bracket 115 frame, a stop on the frame, an extension on said rim engageable with said stop within the recess of the bracket frame, a slop hopper and spring hinges for said basin having portions engageable with said hopper. 120

In witness whereof I have hereunto set my hand in the presence of two witnesses.

GEORGE E. SEYMOUR.
